(57) **CLAIM**

The ornamental design for a massage element, as shown and described.

DESCRIPTION

FIG. 1 is a perspective view of a massage element according to an embodiment;

FIG. 2 is a left side view of the massage element of FIG. 1, the right side view being a mirror image thereof;

FIG. 3 is a front view of the massage element of FIG. 1 thereof;

FIG. 4 is a rear view of the massage element of FIG. 1 thereof;

FIG. 5 is a top view of the massage element of FIG. 1, the bottom view being identical thereto;

FIG. 6 is a perspective view of a massage element according to another embodiment;

FIG. 7 is a left side view of the massage element of FIG. 6, the right side view being a mirror image thereof;

FIG. 8 is a front view of the massage element of FIG. 6 thereof;

FIG. 9 is a rear view of the massage element of FIG. 6 thereof; and,

FIG. 10 is a top view of the massage element of FIG. 6, the bottom view being identical thereto.

The broken lines in the drawings are for the purpose of illustrating portions of the massage element which form no part of the claimed design.
